UNITED STATES PATENT OFFICE

2,564,563

ROTARY CARRY-TYPE SCRAPER

Marion A. Clark, Tulare, Calif.

Application August 1, 1947, Serial No. 765,357

4 Claims. (Cl. 37—126)

1

The present invention has for one object the provision of an improved carry-type scraper for earth working.

It is another object of the present invention to provide a carry-type scraper which includes, in novel assembly, a generally cylindrical bowl having its axis extending transversely and formed adjacent the bottom with a forwardly opening transverse mouth fitted at its lower edge with a cutting and digging blade; and a circumferentially compartmented, reversibly power-actuated rotor in the bowl operative in one direction of rotation to facilitate and accelerate loading of earth into the bowl from said mouth and blade, and in the opposite direction of rotation to readily and evenly discharge the loaded earth from the bowl.

A further object of this invention is to provide a scraper, as above, wherein the rotor includes means thereon cooperating with the bowl to close said mouth for transport of the load with the scraper in carrying position.

An additional object of the invention is to provide a scraper, of the type described, wherein a load can be obtained with a reduced draft load, for the reason that the powered rotor in the bowl recurrently sweeps the dug earth from the digging and cutting blade, thus relieving the resistance to further digging which results from accumulated earth on said blade. As a consequence, larger loads can be obtained with less power, and more rapidly, than otherwise.

It is also an object of the invention to mount the bowl in fixed relation to the main frame of the scraper, so that the unitary structure is rigid and strong.

Another object is to support the front end of the scraper by a wheel truck coupled to the scraper main frame by a novel, adjustable mount; such mount permitting of swivel motion of the truck, while providing means to raise or lower the front end of the scraper main frame to correspondingly regulate the working or carrying positions of the bowl assembly.

A further object of the invention is to provide a practical scraper which will be exceedingly effective for the purpose for which it is designed.

These objects are accomplished by means of such structure and relative arrangement of parts as will fully appear by a perusal of the following specification and claims.

In the drawings:

Fig. 1 is a longitudinal sectional elevation of the scraper, at the start of loading operations.

2

Fig. 2 is a cross section taken directly ahead of the bowl assembly.

Fig. 3 is a side elevation, partly broken away, of the scraper in carrying position.

Referring now more particularly to the characters of reference on the drawings, the improved carry-type scraper comprises a longitudinally extending main frame, indicated generally at 1, which main frame includes, on opposite sides, upper and lower side beams 2 and 3, respectively. At its rear end the main frame 1 is supported by a pair of transversely spaced, rubber-tired wheels 4, and at its forward end the scraper is supported by a swivelly mounted front truck, indicated generally at 5, which includes rubber-tired wheels 6.

A draft tongue 7 projects forwardly from the truck 5 for connection with a tractor. The front truck 5 is secured in connection with the forward portion of the main frame 1 by a vertically adjustable mounting unit, indicated generally at 8, which comprises:

An outer vertical sleeve 9 is fixed, adjacent its upper end, to the forward end of the main frame 1 and projects downwardly therefrom, being initially open at its lower end. An inner vertical sleeve 10 slidably engages in telescopic relation within the outer sleeve 9 from the lower end of the latter. A head plate 11 closes the upper end of the outer sleeve 9, while a bottom plate 12 closes the lower end of the inner sleeve 10. The bottom plate 12 includes a centrally downwardly projecting clevis 13 which straddles, and pivotally connects to, the axle 14 of the front truck 5.

A fluid pressure actuated power cylinder 15 is fixed to the head plate 11 within the telescopic sleeve assembly and projects downwardly therein to engagement, by means of a ball and socket 16, with the bottom plate 12. The power cylinder 15 is controlled by means of a valve regulated, 40 fluid pressure conduit system, indicated in part at 17, whereby the cylinder 15 can be expanded or retracted to raise or lower, respectively, the forward end of the main frame 1.

The bowl assembly of the scraper comprises the following structural arrangement:

A cylindrical bowl, indicated generally at 18, is fixedly mounted in the main frame with the axis of said bowl extending horizontally and transversely; such bowl including end walls 19, 50 a front wall 20, and a rear wall 21. The bowl is open, at the top, between the front and rear walls, as shown.

Adjacent but ahead of the low point of the bowl 18, the same is formed with a generally 55 forwardly opening, transverse loading and dis-

charge mouth 22; the bowl including, as extensions of the end walls 19, skirts 23 at the ends of said mouth to prevent lateral escape of dug earth.

At the rear edge of the mouth the bowl is fitted with a transverse, forwardly and downwardly inclined cutting and digging blade 24.

The cylindrical bowl 18 is fitted, internally, with a rotor, indicated generally at 25, which includes a cross shaft 26 journaled in connection with the end walls 19 and projecting at opposite ends therebeyond. The cross shaft 26 carries a hub 27, and a plurality of generally radial paddles 28 extend outwardly from said hub in equally spaced relation whereby to form a plurality of circumferentially spaced compartments A, B, C, 15 and D, in the bowl. The paddles 28 extend full length of the bowl axially thereof, and project outwardly sufficient to run clear of, but closely adjacent, the walls 20 and 21.

One of the paddles 28 is formed with outwardly divergent paddle sections 29 spaced apart at their outer ends no less than the circumferential width of the mouth 22. In the starting or initial loading position of the scraper, the divergent paddle sections 29 are at the bottom of the bowl directly 20 to the rear of the cutting and digging blade 24. The paddles are secured to circular end plates 28a.

The rotor is arranged for power actuated, reversible rotation in the bowl 18 in the following manner:

A pair of double acting, fluid pressure actuated power cylinders 30 are fixed on the main frame 1 ahead of the bowl 18; said cylinders being secured to opposite sides of the frame and extending laterally inwardly; i. e. with the piston rods 31 disposed adjacent each other but for projection in opposite lateral directions. The double-acting power cylinders 30 are connected in series in a valve regulated fluid pressure conduit system, indicated generally at 32. By means of this conduit system the power cylinders 30 can be simultaneously extended or contracted, which means that the piston rods 30 would act simultaneously, but in opposite directions.

At each end the cross shaft 26 is fitted, externally of the bowl 18, with a pulley 33, and a flexible cable 34 extends, intermediate its ends, over corresponding ones of the pulleys 33. The runs 35 and 36 of each cable extend forwardly and thence turn laterally inwardly about direction-changing sheaves 37 to pass in direction reversing relation about sheaves 38 on different ones of the piston rods 31. From the piston rods 31, the runs extend laterally outwardly to dead-end at any suitable point on the frame or bowl, as shown.

With this arrangement, it will be seen that when the double-acting power cylinders 30 are energized to cause projection of the piston rods 31, the lineal motion of such rods is converted to rotary motion of the pulleys 33 and the rotor 25. Retraction of the piston rods 31 causes rotation of the rotor in the opposite direction.

When the above described scraper is in use, the rotor 25 is initially in the position shown in Fig. 1, and the mounting unit 8 is adjusted to lower the cutting and digging blade 24 into ground engagement, as also shown in such figure. Thereafter, with advance of the implement the blade 24 digs into the earth and the earth, as dug, flows through the mouth 22 into compartment A of the circumferentially compartmented bowl 18.

At the proper time, and after a certain amount of initial advancing movement of the scraper, the power cylinders 31 are actuated so as to turn the

rotor 25 in a clockwise direction, whereupon the adjacent paddle 28 sweeps across the mouth 22, carrying into the compartment A substantially all the loose earth which has then been dug by the blade 24.

As the rotor 25 thus turns, the compartment A closes against the rear wall 21 and the compartment B is moved into earth receiving position relative to the mouth 22, and such compartment begins to load.

The above described cycling is continued until all of the compartments A-D, inclusive, are filled with earth, whereupon the divergent paddle sections 29 are brought into register over the mouth 22 to close the latter and prevent spillage of earth from said bowl. The main frame 1, together with bowl 18, is then raised to the carrying position of Fig. 3 by proper actuation of adjustment of the mounting unit 8.

When the scraper reaches the point of discharge the power cylinders 30 are actuated in a direction to cause counter-clockwise rotation of the rotor 25, with the result that the compartments are successively brought into register with the mouth 22, and the load in such compartments discharged through said mouth with an even spreading action.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent are desired:

1. A carry-type scraper comprising a wheel-supported main frame, a generally cylindrical bowl mounted on the main frame, said bowl having a transverse, forwardly opening mouth adjacent the bottom thereof, a cutting and digging blade on the bowl at the rear edge of the mouth, a circumferentially compartmented, peripherally open rotor journaled in the bowl in cooperative relation to said mouth and blade, and power means arranged to actuate the rotor; said power means being a fluid pressure actuated power cylinder assembly, and instrumentalities between said power cylinder assembly and rotor operative to convert lineal motion of the former to rotation of the latter; said instrumentalities including a shaft on the rotor, a pulley on the shaft, and a flexible element extending intermediate its ends about the pulley; the power cylinder assembly being operatively connected to said flexible element to pull on one end portion thereof and pay out the other end portion thereof, reversibly.

2. A carry-type scraper comprising a wheel-supported main frame, a generally cylindrical bowl mounted on the main frame, said bowl having a transverse, forwardly opening mouth adjacent the bottom thereof, a cutting and digging blade on the bowl at the rear edge of the mouth, a circumferentially compartmented, peripherally open rotor journaled in the bowl in cooperative relation to said mouth and blade, and power means arranged to reversibly actuate the rotor; said power means comprising a pair of double acting, fluid pressure actuated power cylinder mounted on the main frame, a shaft

on the rotor projecting from opposite ends thereof, a pulley on each end of the shaft, a pair of flexible elements engaging about the pulleys intermediate the ends of said elements, and means to simultaneously actuate said double acting power cylinders, the latter being arranged in cooperation with said flexible elements to cause to and fro motion thereof upon simultaneous operation of the power cylinders in one direction and in the reverse direction.

3. A scraper as in claim 2 in which the power cylinders are mounted transversely on the main frame and include laterally inwardly projecting piston rods, a double sheave on each piston rod, and direction-changing sheaves on the main frame adjacent the sides directing the pair of runs of corresponding flexible elements lengthwise of the power cylinders, the runs of each pair doubling about sheaves on separate piston rods and thence dead-ending on the frame.

4. A carry-type scraper comprising a wheel-supported main frame, a generally cylindrical bowl mounted on the main frame, said bowl having a transverse, forwardly opening mouth adjacent the bottom thereof, a cutting and digging blade on the bowl at the rear edge of the mouth, a horizontal, transverse shaft extending axially through the bowl, a hub on the shaft, transversely extending, circumferentially spaced

paddles radiating from the hub to form a circumferentially compartmented rotor in said bowl, and power means arranged to turn the rotor to successively register the compartments with the mouth; said last named means including pulleys on opposite ends of the shaft, cables leading intermediate their ends about the pulleys, and a double acting power cylinder assembly on the frame, the cables being guided and connected to said cylinders in a manner to convert lineal motion of the cylinders to simultaneous turning motion of the pulleys in the same direction.
